Patented June 30, 1914.

UNITED STATES PATENT OFFICE.

HERSCHEL RAGSDALE, OF CEDAR VALE, KANSAS.

STAPLING-MACHINE.

1,101,659.

Specification of Letters Patent. Patented June 30, 1914.

Application filed November 20, 1913. Serial No. 802,075.

To all whom it may concern:

Be it known that I, HERSCHEL RAGSDALE, a citizen of the United States, residing at Cedar Vale, in the county of Chautauqua and State of Kansas, have invented certain new and useful Improvements in Stapling-Machines, of which the following is a specification.

This invention relates to stapling machines, and my object is to produce a stapling machine by which staples can be arranged in position for driving without being touched by hand after they are placed in the machine.

15 A further object is to produce a machine of this character having a lever-actuated mechanism for disposing the staples successively in operative position, together with means for insuring the feeding of one staple at a time and retaining the rest of the staples in proper position in the magazine.

With these general objects in view and others as hereinafter appear, the invention consists in certain novel and peculiar features of construction and organization as hereinafter described and claimed; and in order that it may be fully understood reference is to be had to the accompanying drawings, in which—

30 Figure 1, is a side view of a stapling machine embodying my invention. Fig. 2, is an inverted plan view of the same. Fig. 3, is a horizontal section on the line III—III of Fig. 1. Fig. 4, is a section on line IV—IV of Fig. 2. Fig. 5, is a fragmentary side view showing the shifting shield elevated in full lines and in dotted lines swung to inoperative position to permit the machine to be charged with staples. Fig. 6, is a 40 perspective of the staple cut-off member.

In the said drawings, 1 indicates a magazine of U-shape in cross section, made from sheet metal. At one end the metal is bent to form a handle 2. At the opposite end it is pointed by preference, and is split centrally from the point for a suitable distance, the sides of the split portion being bowed outwardly at 3 to form a substantially cylindrical chamber 4 in communication with the magazine. Rearward of the cylindrical chamber 4, the curved portion of the magazine is cut away to provide an opening 5, and forward of said chamber the ends of the machine fit flatly together and are so secured in rigid relation by screws or rivets 6.

7 indicates a cylindrical staple-driving pin fitting in chamber 4 and capable of sliding longitudinally or of turning in said chamber, and at its outer end the pin is 60 provided with an outwardly projecting flange 8.

9 is a helical spring fitting around the pin 7, and interposed between the bowed portion 3 of the magazine and the flange 65 or head 8 of the pin to normally hold the latter retracted, as shown most clearly in Fig. 4. The lower portion of the pin is toothed as at 10 to constitute a cog segment and in its normally rear side it is provided 70 with a longitudinally extending recess 11 and a socket 12, in the base and near the lower end of the recess. Pivoted in said recess is a catch 13, provided in its rear edge with a notch forming an abrupt downwardly-disposed shoulder 14 and a rounded 75 upwardly disposed shoulder 14^a. It is also provided with a projection 15 for receiving one end of a coil spring 16 mounted within said socket and tending to hold the rear 80 edge of the catch flush with the outer face of the pin. One side wall of the magazine, preferably the right-hand wall is provided with a longitudinal slot 17, which extends through the corresponding bowed portion 85 3, and in line with and forward of said slot a headed guide pin 18 projects from the front portion of the machine.

19 is a reciprocatory bar arranged at the right hand side of the magazine and near 90 its front end extending through the slot 17 and provided in its inner edge with rack teeth 20, engaging the teeth 10 of the cog segment formed on the pin 7. At the front end of said series of rack teeth 20 the 95 reciprocatory bar bends inward toward the front end of the magazine wall and is provided with a longitudinal slot 21, engaging the headed guide pin 18. At its rear end the bar 19 is pivoted at 22 to a bell crank 100 lever 23, the upper arm 24 of the lever being widened so as to constitute a latch which can be conveniently depressed by the thumb of the hand grasping the handle. Attached to said thumb latch at one end and at its 105 opposite end to the magazine wall is a retractile spring 25 for holding the reciprocatory bar at its forward limit of movement as shown in Figs. 1 and 3, the rack teeth of said bar at such time holding the pin 110 with its recess 11 disposed rearwardly or toward the handle as shown.

26 is a stringer bar for the staples, the same being secured rigidly at its rear end in the handle and terminating at its front end adjacent to the pin 7, and for the entire 5 length of the magazine chamber said stringer bar is spaced from the walls of the chamber in order to accommodate the legs of the staples. The lower edge of the bar 26 is provided with forwardly disposed rack 10 teeth 27.

28 is an inverted-U shaped follower fitting 15 slidingly on the stringer bar, and pivoted between the arms of the follower is a catch 29 for successive engagement with the teeth of the stringer bar, said catch being held normally 20 in engagement with the teeth of the stringer bar by a spring 30 secured to said catch at one end and at its opposite end bearing against a pin 31. At its rear end 25 the catch is provided with a thumb piece 32 so that by applying rearward pressure therein, the catch can be disengaged from the stringer bar and slid longitudinally thereon, the catch reengaging the stringer bar under the action of the spring 30, the instant 30 said thumb piece 32 is released.

33 is a shifting shield for normally closing the feed opening 5, and at one side the shield is provided with a depending slotted 35 arm 35 to fit snugly against the corresponding side wall of the magazine. Engaging the slot 36 of said arm is a headed pin 37 projecting from said side wall of the magazine, a coiled spring 38 being mounted 40 upon said pin and bearing at its opposite ends against the head of the same and the slotted arm to hold the shield yieldingly in either open or closed position. Secured to one of the side walls of the magazine by 45 screws 42 is a bracket member 43, one end of which is folded to form a guideway 44 for slidingly receiving the stem 45 of a staple cut-off member 46. This member 46 is adapted to be reciprocated vertically 50 through the feed opening 5 at the front end of the bar 26, in order to bring a staple separating lug 47 in between the front end of said bar and the driving pin 7 and thereby retain upon said bar all of the staples 39 except the one being driven. The member 46 is operated by means of a plate 48 carried 55 by the bar 19 alongside the guideway 44 and provided with a pair of inclined cam edges 49 for engagement with the shoulders 50 formed on the stem 45 of the member 46, the arrangement being such that in the forward position of the bar 19 the upper edge 49 of the plate 48 acts to maintain the member 46 elevated. From this construction it will be 60 seen that on reciprocation of the bar 19 the plate 48 will be moved to cause its edges 49 alternately to raise and lower the cut-off member 46, thereby permitting one staple at a time to be fed and retaining the remaining staples on the stringer bar. Assum-

ing that the shield is open as shown in Fig. 5, the operator can insert the staples 39 into the magazine through said opening until they rest astride the stringer bar. If the machine is held slightly tilted, the staples 70 will successively slide rearward upon the bar, the first one inserted coming to rest against the follower, the second one against the first, the third against the second, and so on, and if it is desired to charge the magazine to its full capacity, the follower will be adjusted rearwardly upon the stringer bar until it comes in contact with the pair of filling strips 40, fitting between the sides of the handle and the stringer bar, as indicated in Fig. 2. The follower is then shoved forward to cause the foremost staple to be advanced beyond the front end of the stringer bar into the recess 11 of the pin, the bridge or head end of the staple assuming a 80 position between the shoulders of the catch 13. The operator then applies pressure upon the thumb latch 24 to overcome the resistance of spring 25 and impart rearward movement to bar 19, this movement through 85 the engagement of the teeth 20 of said bar with the cog segment 10, imparting one-fourth of a revolution to the pin 7, the said staple being carried around within chamber 4 with said pin and latch. The same movement of the arm 19 operates the plate 48 to lower the member 46 to dispose its lug 47 in front of the remaining staples, thereby 90 retaining the latter in proper position on the stringer bar. The machine is then placed 95 against the object into which the staple is to be driven and over a wire extending across the face of such object, or the machine will be arranged at right angles to said wire so that the latter may extend through the oppositely disposed notches 41 formed in the lower edges of the outwardly bowed portions 3. With a hammer held in the other hand the pin is then struck sharply to cause 100 it to overcome the resistance of spring 9, 110 and through shoulder 14 of the catch drive the staple over the wire into the post or other object referred to, the reexpansion of the spring 9 causing the pin to withdraw with sufficient force to overcome the resistance of spring 16 to effect inward movement of the lower end of the pivoted catch 13 and the consequent disengagement of the same from the staple. As this occurs, the pressure 115 on the thumb latch 24 is removed to permit the spring 25 to readvance bar 19 and effect the backward rotation of the pin and the elevation of member 46 to their original positions. The machine is then tilted sufficiently to permit the staples and follower to 120 move forward by gravity in the magazine to dispose another staple within the recess of the pin, and then the operations in the order traced may be repeated to place and drive another staple. 125 130

From the above description it will be apparent that I have produced a stapling machine possessing the features of advantage enumerated as desirable in the statement of the objects of the invention, and I wish it to be understood that while I have illustrated and described the preferred embodiment of the invention, I do not desire to be restricted to the exact details of construction shown and described as obvious modifications will suggest themselves to one skilled in the art.

I claim:

1. A stapling machine, having a magazine, a cylindrical chamber at the front end of and communicating at its rear side with the magazine, a pin fitting in said chamber and movable endwise therein and provided at its rear side with a recess, a spring actuated catch in the said recess and movable with and independently of the pin and provided at its rear edge with an upwardly disposed shoulder, and means to advance a staple from the magazine into the said recess and onto said shoulder.

2. A stapling machine having a magazine, a cylindrical chamber at the front end of and communicating at its rear side with the magazine, a pin fitting in said chamber and movable endwise therein and provided at its rear side with a recess, a spring actuated catch in the said recess and movable with and independently of the pin and provided at its rear edge with an upwardly disposed shoulder, means to advance a staple from the magazine into the said recess and onto said shoulder, and means to turn the pin to face its recess and the staple-carrying catch laterally.

3. A stapling machine having a magazine, a cylindrical chamber at the front end of and communicating at its rear side with the magazine, a pin fitting in said chamber and movable endwise therein and provided at its rear side with a recess, a spring-actuated catch in the recess and movable with and independently of the pin and provided at its rear edge with an upwardly disposed shoulder, means to advance a staple from the magazine into said recess and into said shoulder, means to turn the pin to face its recess and the staple-carrying catch laterally, and means to retract the pin and disengage the catch from said staple after the pin has been forced endwise in the said chamber to cause the catch to drive said staple.

4. A stapling machine having a magazine, a cylindrical chamber at the front end of and communicating at its rear side with the magazine, a pin fitting in said chamber and movable endwise therein and provided at its rear side with a recess, a spring-actuated catch in the said recess and movable with and independently of the pin and provided at its rear edge with an upwardly disposed shoulder, means to advance a staple from the magazine into the said recess and onto

said shoulder, means to turn the pin to face its recess and the staple-carrying catch laterally, means to retract the pin and disengage the catch from said staple after the pin has been forced endwise in the said chamber to cause the catch to drive said staple, and means to return the pin-turning means to its original position to dispose said pin and catch in position to receive another staple.

5. A stapling machine having a magazine, a cylindrical chamber at the front end of and communicating at its rear side with the magazine, a pin fitting in said chamber and movable endwise therein and provided at its rear side with a recess, a spring-actuated catch in the said recess and movable with and independently of the pin and provided at its rear side with an upwardly disposed shoulder, means to advance a staple from the magazine into said recess and onto said shoulder, means to turn the pin to face its recess and the staple-carrying catch laterally, and a spring to retract the pin and disengage the catch from said staple after the pin has been forced endwise in the said chamber to cause the catch to drive said staple.

6. A stapling machine having a magazine, a cylindrical chamber at the front end of and communicating at its rear side with the magazine, a pin fitting in said chamber and movable endwise therein and provided at its rear side with a recess, a spring-actuated catch in the said recess and movable with and independently of the pin and provided at its rear edge with an upwardly disposed shoulder, means to advance a staple from the magazine into said recess and onto said shoulder, means to turn the pin to face its recess and the staple carrying catch laterally, and a coiled spring around the pin and bearing against the same and the magazine to retract the pin and disengage the catch from said staple after the pin has been forced endwise in the said chamber to cause the catch to drive said staple.

7. A stapling machine having a magazine, a cylindrical chamber at the front end of and communicating at its rear side with the magazine, a pin fitting in said chamber and movable endwise therein and provided at its rear side with a recess, a spring-actuated catch in the said recess and movable with and independently of the pin and provided at its rear edge with an upwardly disposed shoulder, means to advance a staple from the magazine into the said recess and onto said shoulder, an endwise movable bar geared to the pin to turn the same, and a thumb latch to move the bar endwise.

8. A stapling machine having a magazine, a cylindrical chamber at the front end of and communicating at its rear side with the magazine, a pin fitting in said chamber and movable endwise therein and provided at its

4
rear side with a recess, a spring-actuated catch in the said recess and movable with and independently of the pin and provided at its rear edge with an upwardly disposed 5 shoulder, means to advance a staple from the magazine into the said recess and onto said shoulder, an endwise movable bar geared to the pin to turn the same, a thumb latch to move the bar endwise, and a retractile spring to effect opposite or return endwise movement of said bar.

9. A stapling machine having a magazine provided with a feed opening at its front end and a cylindrical chamber extending at 15 right angles to and communicating at its rear side with the magazine at the front end thereof, a stringer bar for supporting staples astride and side by side in the magazine and underlying the feed opening and terminating 20 at the rear side of said chamber, a pin fitting in said chamber and susceptible of turning and endwise movement therein and provided with a recess in its rear side to receive a staple from the stringer bar, a catch within 25 said recess, provided with an upwardly-disposed cam shoulder to underlie and a downwardly disposed shoulder to overlie the head or bridge end of the staple received by said recess, means to shift a staple from the end 30 of the stringer bar into said recess, a spring to hold the catch in position to receive the head end of said staple, means to rotate the pin, and a shifting shield to cover or expose the feed opening.

25 10. A stapling machine having a magazine, a cylindrical chamber at the front end

of and communicating at its rear side with the magazine, a pin fitting in said chamber and movable endwise therein and provided at its rear side with a recess, a spring-actuated catch in the said recess and movable with and independently of the pin and provided at its rear edge with an upwardly disposed 40 shoulder, means to advance a staple from the magazine into the said recess and 45 onto said shoulder, and cut-off means for separating said staple from the remaining staples and retaining the latter in said magazine.

11. A stapling machine having a magazine, a cylindrical chamber at the front end of and communicating at its rear side with the magazine, a pin fitting in said chamber and movable endwise therein and provided at its rear side with a recess, a spring-actuated catch in said recess and movable with and independently of the pin and provided at its rear edge with an upwardly disposed 50 shoulder, means to advance a staple from the magazine into the said recess and onto said shoulder, means to turn the pin to face its recess and the staple-carrying catch laterally, and cut-off means operated by said turning 55 means and acting to separate said staple from the remaining staples and retaining the latter in said magazine.

In testimony whereof, I affix my signature, in the presence of two witnesses.

HERSCHEL RAGSDALE.
